(57) **CLAIM**

The ornamental design for a wireless bedwetting alarm kit, as shown and described.

DESCRIPTION

FIG. 1 is a perspective view of the case of the wireless bedwetting alarm kit showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the wireless bedwetting alarm of the kit;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of a wireless bedwetting sensor of the kit;

FIG. 18 is another perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof;

FIG. 25 is a perspective view of the alarm and sensor stored in the case; and,

FIG. 26 is a perspective view of the case shown in a closed state and shown separately for ease of illustration.

The broken lines in the drawings depict portions of the wireless bedwetting alarm kit that form no part of the claimed design.

1 Claim, 26 Drawing Sheets
